CLOSURE FOR BOTTLES AND JARS

Michael A. Greene and Daniel M. Gray, Wheeling, W. Va., assignors to Hazel-Atlas Glass Co., Wheeling, W. Va., a corporation of West Virginia

Application April 15, 1933, Serial No. 666,374

3 Claims. (Cl. 215—40)

This invention relates to metallic caps for bottles and jars of the side-seal type in which a gasket is mounted in the skirt of the cap and makes sealing contact with the side wall of the container when the cap is forced down to its final position.

One of the primary objects of the invention resides in improving caps of this type so that they may be more readily removed from the jar.

10 A further object of the invention consists in so forming the lower edge of the skirt of the cap that it will serve not only to retain the gasket in position within the cap but also will provide a greater area for the application of the pry-off tool to prevent the slipping of the tool during removal of the cap.

Another object of the invention resides in modifying the skirt construction so as to stiffen the same to prevent undue distortion during the 20 prying-off operation, thereby aiding in removal of the cap as well as preserving its reseal value.

Other objects and advantages of the invention will be apparent from the following description when taken in connection with the accompanying 25 drawing, in which,

Figure 1 is a vertical sectional view of one form of cap about to be applied to the container.

Figure 2 is a similar view showing the cap in sealing position.

30 Figure 3 is a vertical sectional view of a modified construction of cap about to be applied to the container; and

Figure 4 is a similar view showing the modified cap in sealing position.

35 The numeral 1 indicates a jar or other receptacle provided with a mouth 2 and a closure 3 for sealing the same. Below the mouth 2, and spaced only slightly below the closure 3 when it is in sealing position, the jar is provided with an annular flange 4 having a substantially horizontal upper surface 5 for cooperation with a pry-off tool.

The exterior wall of the jar adjacent the mouth 2 is preferably of cylindrical form, as indicated by the numeral 6, to provide a centering portion for the closure 3 when it is loosely mounted on the jar in the initial step of sealing the same. Below the cylindrical portion 6 the jar shown in Figs. 1 and 2 is provided with a bead 7 about which the gasket is forced when the closure is moved to sealing position. This bead is slightly rounded, whereas the bead 7' shown in Figs. 3 and 4 is somewhat sharpened. The closure, to be described, is used with either form of finish, and both give a good seal; but the bead 7 per-

mits easier removal of the closure, while bead 7' furnishes a higher holding power.

Referring now to the form of closure shown in Figs. 1 and 2, the numeral 8 indicates the skirt of the cap provided with an inset portion 9 at its upper end. This inset portion has an internal diameter approximating that of the cylindrical portion 6 of the finish of the jar, so that it can receive the upper end of the jar. The inset portion 9 of the skirt also provides a horizontal shelf 10 or abutment 10 which serves as an upper confining wall for a gasket. The gasket, which is of the side seal type, is indicated by the numeral 11. The internal diameter of the gasket is slightly greater than the diameter of the cylindrical portion 6 of the finish, so that the cap and gasket will easily drop over the cylindrical portion of the finish, and of course its diameter is substantially less than the external diameter of the bead 7 of the jar, so as to provide a sealing fit between 20 these parts.

Formed on the lower edge of the skirt 8, is a rolled edge or bead 12. The bead may be rounded or slightly flattened as shown so long as it provides inwardly and outwardly extending projections 13 and 14. The projection 13 forms the lower support for the gasket 11 cooperating with the skirt 8 and upper flange 10 to securely hold the gasket in properly assembled relation with the closure 3.

The outwardly directed portion 14 of the bead 12 very considerably aids in the removal of the cap, for this portion plus the inwardly directed portion greatly increases the pry-off area thereby preventing slipping of the pry-off tool during the 35 removal of the cap, which is a common difficulty encountered in the removing of caps.

The bead 12, taken as a whole, has a further function in that it reinforces the skirt of the closure against distortion by the prying-off tool. 40 This action of the bead 12 not only aids in the removal of the closure but also by minimizing distortion of the closure preserves its reseal value. It will thus be seen that the rolled edge 12 including the inwardly and outwardly projecting 45 elements 13 and 14 is a very substantial improvement in closures of this type in that it performs three distinct functions, namely, supports the gasket 11, greatly facilitates removal of the closure from the container, and assists in maintaining 50 the shape of the closure for reseal purposes.

In the modified construction of the closure shown in Figures 3 and 4, and referred to by numeral 15, the necked-in portion 16 as well as the flange 17, skirt 18 and gasket 19 correspond with 55

the same elements in the closure 3, but other means have been provided for performing the several functions of the bead 12 of the previously described form of the invention.

5 In this modified form of closure the lower edge of the skirt is first bent outwardly in a substantially horizontal direction as indicated by numeral 20, and is then doubled upon itself as indicated at 21 to provide an inwardly directed 10 flange 22 for supporting the gasket 19. In other words the metal of the lower edge of the skirt is bent to provide a flange which extends both inwardly and outwardly beyond the skirt. This construction has all of the advantages of the 15 first-described form of the invention; the projection 22 supporting the gasket, the projection 21 providing the additional area upon which the prying-off tool can act, so that the tool has less chance of slipping, thereby facilitating removal 20 of the cap, and the two projections together providing the necessary reinforcement to minimize distortion of the closure and enhance its reseal 25 value.

From the foregoing it will be apparent to those 25 skilled in the art that a materially improved side-seal closure has been provided in that without sacrificing any of the sealing qualities of the closure the same may be readily removed with any 30 convenient tool, and that by reason of the reinforcement of the closure little or no distortion will result, thereby permitting reuse of the closure in temporarily sealing the container from time to time while the contents are being used.

In accordance with the patent statutes we 35 have described herein the preferred embodiments of the invention, but obviously various changes may be made in the details of construction without departing from the spirit of the invention, and all such changes are intended to be included 40 within the scope of the appended claims.

What we claim is:

1. In combination with a jar having a side-

seal finish, an annular ledge spaced slightly below the finish, a preformed closure including a top portion, a skirt depending therefrom, a gasket mounted on the inner face of the skirt, a bead formed on the lower edge of the skirt, said bead being partially flattened and having portions extending inwardly and outwardly from the skirt, the inwardly extending portion of the bead serving as a support for the gasket and the inwardly and outwardly extending portions in co-operative relation with and spaced from the ledge to facilitate removal of the closure. 5 10

2. In combination with a jar having a side-seal finish, an annular ledge spaced slightly below the finish, a preformed closure including a top portion, a skirt depending therefrom, a gasket mounted on the inner face of the skirt and extending the full height of the skirt, the lower portion of the skirt being bent outwardly to form a horizontal flange projecting laterally beyond the skirt, and then bent inwardly against itself, the free end of the inbent portion projecting inwardly of the skirt, the inwardly extending portion serving as a support for the gasket, and the inwardly and outwardly extending portions in 25 cooperative relation with and spaced from the ledge to facilitate removal of the closure. 15 20

3. In combination a jar having a finish including an annular bead adapted to cooperate with the gasket of a closure to lock the closure in sealing position, an annular ledge spaced slightly below the finish, a preformed closure including a top portion, a skirt depending therefrom, a gasket mounted on the inner face of the skirt, the lower edge of the skirt being bent to provide inwardly and outwardly extending projections, said inward projection forming a support for the gasket and the inward and outward projections in cooperative relation with and spaced from the ledge to facilitate removal of the closure. 30 35 40
